DESIGN FOR A PLUG VALVE BODY

Eugene C. Brisbane, York, Pa., assignor to S. Morgan Smith Company, York, Pa., a corporation of Pennsylvania

Application April 7, 1936, Serial No. 61,985

Term of patent 14 years

To all whom it may concern:

Be it known that I, Eugene C. Brisbane, a citizen of the United States, resident of York, in the county of York and State of Pennsylvania, have invented a new, original, and ornamental Design for Plug Valve Bodies, of which the following is the specification, reference being had to the accompanying drawings, forming part thereof.

Fig. 1 is a perspective view of a plug valve body, showing my new design;

Fig. 2 is a top plan view of the valve body of Fig. 1;

Fig. 3 is a front elevation of a valve body of Fig. 1; and

Fig. 4 is a side elevation of the valve body of Fig. 1.

I claim:

The ornamental design for a plug valve body, substantially as shown.

EUGENE C. BRISBANE.
